UNITED STATES PATENT OFFICE.

JULIUS F. RUTZ AND ARNOLD O. RUTZ, OF MILWAUKEE, WISCONSIN, ASSIGNORS TO
RULU GAS LIGHTER COMPANY, OF MILWAUKEE, WISCONSIN.

IGNITER-TORCH.

1,280,859.

Specification of Letters Patent.

Patented Oct. 8, 1918.

Application filed July 13, 1914. Serial No. 850,689.

To all whom it may concern:

Be it known that we, JULIUS F. RUTZ and ARNOLD O. RUTZ, both citizens of the United States, and residents of Milwaukee, in the county of Milwaukee and State of Wisconsin, have invented certain new and useful Improvements in Igniter-Torches; and we do hereby declare that the following is a full, clear, and exact description thereof.

10 Our invention refers to gas lighters common to a series of burners grouped thereabout and particularly to that type described in a patent issued to J. F. Rutz and J. K. Luethe November 21, 1911, for igniter torches, No. 1,009,184.

The object of our present invention is to increase the efficiency and to simplify the construction of the igniter torch referred to in its various details, whereby the cost of 20 manufacture is reduced and its utility and durability is increased.

The specific objects of our invention are to provide a pilot-light supply-tube that is entirely incased within the torch supply-tube, whereby the said pilot-supply tube is protected, with the exception of the tip or nozzle end, which end extends through its torch-tube, the same being bent upwardly to the desired position for igniting the main 30 gas supply that is discharged from the torch-head, and to provide an incasing bell for the torch-head and pilot nozzle that is entirely detached from said head, the bell being provided with a retaining spider that 35 engages a portion of the head and a key or saddle recess, which recess is adapted to straddle the shank of the torch-head, whereby the bell is keyed in a position relative to said torch-head to automatically permit

40 registration of a series of torch-head apertures and firing ports in the bell. By this arrangement the bell is capable of being removed for convenience in cleaning the several parts, which parts have been found in 45 practice to be subject to carbon or sooty deposits.

With the above objects in view the invention consists in certain peculiarities of construction and combination of parts as hereinafter set forth with reference to the accompanying drawings and subsequently claimed.

In the drawings

Figure 1 illustrates a sectional elevation

of an igniter torch embodying the features of our invention;

Fig. 2, a detailed cross-section through the torch incasing bell showing the torch-head fitted therein, and

Fig. 3, an enlarged sectional plan view of the tip, the section being indicated by line 60 3—3 of Fig. 1, the said section showing the relative arrangement of the discharge apertures and the vent apertures therein.

Referring by characters to the drawings, 1 represents a gas supply pipe for feeding of 65 gas to a series of burners, not shown, to which pipe is connected the torch supply tube 2 through the medium of a controlling valve 3. The valve is incased in a shell 3', which shell is formed with a by-pass 4, the 70 same extending through the shell and in communication with the supply-pipe. The by-pass 4 is under control of a regulating screw-plug 5, whereby the flow of gas is restricted or increased as desired. The mouth 75 of the by-pass channel that extends into the torch supply-tube 2 is threaded for the reception of one end of a pilot-tube 6, which tube, in assemblage, is inserted through the outer open end of the torch supply-tube 2, 80 the said pilot-tube being initially straight from end to end. The pilot-tube 6 also passes through an aperture in an elbow 7, which elbow constitutes the shank portion of a torch-head. That branch of the elbow 85 7, which is alined with the tube opening, is threaded for engagement with the correspondingly threaded open end of the torch supply-tube 2, it being understood that the elbow is first slipped over the outer end of 90 the pilot supply tube 2, which tube passes beyond the elbow.

The vertical branch of the elbow has fitted thereto a thimble 8, which thimble carries a tip 9 at its discharge end, the same being 95 provided with a series of radially disposed gas-discharge apertures 9' to complete the torch-head. The tip is also provided with a leak aperture 10 that is employed for the purpose of permitting a small flow of gas 100 under the radially disposed discharge apertures 9' and between a pair of the same but upon a lower plane. To complete the igniter torch the open extended end of the pilot supply tube 6 is bent upwardly in approximate alinement with the torch thimble to

form a pilot nozzle 6', the mouth of which nozzle is positioned adjacent to the leak aperture 10, whereby escaping gas therefrom will be ignited.

5 In order to prevent leakage around the pilot supply-tube 6 where it passes through the aperture in the elbow or shank portion of the torch-head, we preferably calk the joint between these parts, which calk joint 10 also prevents displacement of the tube.

A removable bell 12 is adjusted to the torch-head, the same being provided with a series of firing ports 12, which ports are radially and horizontally alined with the series of torch discharge apertures 9'. In order to insure the radial alinement between the firing ports and discharge apertures, the lower open edge of the bell is provided with a semi-circular key recess 14, which recess is 15 arranged to straddle the horizontal branch of the elbow 7 that constitutes the shank of the torch-head. The bell 12 is also provided with a centrally apertured retaining spider 15, the aperture of which is fitted 20 over the thimble 8 of the torch-head and one face of the spider is adapted to rest upon the upper juxtaposed end face of the vertical branch of the elbow, it being understood 25 that the pilot nozzle 6' extends between arms 30 of the spider and above the same.

Hence it is apparent from the foregoing description that the removable bell is so keyed that it is impossible to insert the same over the torch and pilot-light without properly alining the firing holes with the torch tip discharge apertures.

It is also manifest that the pilot supply-tube 6 is entirely incased within the torch supply tube 2 and protected, with the exception of the projecting pilot nozzle, which nozzle, owing to its closely nested position relative to the torch-head, is not liable to damage. Furthermore this construction renders the device self-contained and compact, 45 a desirable feature in shipment.

It is also apparent that the tip apertures and mouth of the pilot nozzle 6' can readily be cleaned, if choked, by removal of the bell, the dome of which bell can also be cleansed 50 of any sooty or carbon deposits, which deposits are due to foreign gases and spent products of combustion. After the parts are all thoroughly cleaned it will be observed that the bell is so keyed that it is impossible 55 for the housewife or other unskilled operator to replace the same other than in a correct position relative to the torch-head and firing ports.

By arranging the leak aperture 10 of the 60 tip in the position shown, when ignition takes place from the pilot-flame, a volume of

hot burnt gases will be confined by the hood about the tip to thus insure ignition of all the jets simultaneously and thus the accumulation of a pocket of gas followed by an explosion thereof is avoided, which latter result has been found in practice where the vent-aperture for supplying the torch-head has been placed at a considerable distance below said head. 65 70

We claim:

1. In an igniter torch having a supply tube provided with an upturned elbow, and a thimble in threaded union with the vertical leg of the elbow, the thimble being provided with a firing tip; the combination of a removable bell having firing ports, the lower edge of said bell being provided with a semi-circular key recess adapted to straddle the horizontal branch of the elbow, whereby said bell is held in a fixed position against horizontal play, and a spider carried by the bell and resting on the elbow and having a central aperture loosely fitted over the thimble. 75 80 85

2. In an igniter torch including a supply tube having one end upwardly directed and provided with firing jets; the combination of a removable bell having firing ports and being provided with a recess in its lower edge portion adapted to straddle the horizontal portion of the tube, and a spider carried by the bell and apertured to receive the upwardly directed end of the tube. 90

3. A lighter of the class described comprising a valve casing having a recess, said casing having a main fluid passage-way and a fluid by-pass, both opening into said recess, a torch supply pipe closed throughout its length and having one end secured in 100 said recess and communicating with the main passage-way, a torch head on the free end of said supply pipe, and a pilot supply tube having its major portion disposed within the supply pipe, one end being disposed 105 in said recess and connected with the valve casing in communication with said fluid by-pass, its other end being extended through the wall of the supply pipe adjacent its free end and disposed externally thereof in jux- 110 position to the torch head. 110

In testimony that we claim the foregoing we have hereunto set our hands at Milwaukee in the county of Milwaukee and State of Wisconsin in the presence of two 115 witnesses.
